UNITED STATES PATENT OFFICE

2,545,037

ROTARY DRILL BIT APPARATUS

Archer W. Kammerer, Fullerton, Calif.

Application April 8, 1949, Serial No. 86,161

17 Claims. (Cl. 255—76)

1

The present invention pertains to drill bits, and is more particularly directed to rotary bits embodying expandible cutters for drilling holes below casing, or other well conduits, that are greater in diameter than the inside diameter of the casing string through which the bits are capable of passing.

This application is a continuation-in-part of my applications for "Rotary Drill Bits," Serial No. 597,744, filed June 6, 1945, now Patent No. 2,466,991; "Expandible Rotary Drill Bits," Serial No. 636,806, filed July 29, 1946; and "Expandible Drill Bit," Serial No. 43,789, filed August 12, 1948.

In expandible drill bits of the type described in my above-identified applications, the expandible cutters can be held normally in retracted position by a latch device. The cutters may be held in that condition to permit lowering of the drill bit through an open well bore to the depth at which the hole enlarging operation is to commence. When this point is reached, the latch device is removed, to allow the cutters to be expanded outwardly to a position enabling their production of an enlarged diameter hole.

Following their outward expansion to their fullest extent, the cutters are locked in that position by a telescopic device movable behind the cutter supports. Fluid can be pumped down the drill string and telescopic device for action upon the expandible cutters, to maintain them free from formation cuttings and insure their proper penetration into the formation.

An object of the present invention is to provide a rotary drill bit of the character above-indicated, embodying a modified device for retaining the expandible cutters initially in retracted position, and for releasing such cutters when their outward expansion is desired.

Still another object of the invention is to provide a latch arrangement for holding the cutters initially in retracted position, and which cutters are released, when desired, by positively acting mechanical instrumentalities forming part of the drill bit itself.

A further object of the invention is to provide a rotary expandible drill bit, in which the latch device for holding the cutters initially retracted is released by a telescopic mandrel, or similar device, which serves to hold the cutters in their outwardly expanded position.

Rotary expandible drill bits are sometimes employed in connection with a non-expandible bit, which is adapted to act upon the bottom of the hole and form the central portion of the hole. In general, the major portion of the formation

2

material is removed by this drill bit, the expandible drill bit enlarging the well bore thus produced.

An object of the present invention is to provide a combined non-expandible and expandible drill bit arrangement, in which assurance is had that a major portion, if not all, of the drilling mud, or other circulating fluid, is pumped downwardly to the non-expandible bit, to insure the removal of the cuttings which it produces, and the maintenance of its cutter elements in a relatively clean condition.

Yet another object of the invention is to provide an expandible rotary drill bit, in which the cutters are locked outwardly in their laterally expanded position by a telescopic mandrel which is capable of insuring a supply of a large volume of drilling fluid to a non-expandible drill bit positioned below the expandible drill bit.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limiting sense, since the scope of the invention is best defined by the appended claims.

Referring to the drawings:

Fig. 1 is a side elevation, on a reduced scale, showing a drill bit apparatus embodying the invention;

Fig. 2 is a longitudinal section, taken along the line 2—2 on Fig. 3, of the drill bit apparatus disposed within a well bore, with the parts of the expandible bit portion occupying their initial retracted position;

Fig. 3 is a cross-section taken along the line 3—3 on Fig. 2;

Fig. 4 is an enlarged view similar to Fig. 2 of the apparatus, with the expandible cutters locked in their outwardly expanded positions;

Figs. 5, 6 and 7 are cross-sections taken along the lines 5—5, 6—6 and 7—7, respectively, of Fig. 4.

As shown in the drawings, the rotary drill bit apparatus A is attached to a string of drill pipe B, by means of which it is lowered through a well casing C in a well bore D to a point below a casing shoe E, at which the hole is to be deepened and enlarged to a diameter greater than the in-

side diameter of the well casing through which the apparatus must pass.

The apparatus includes a non-expansive pilot bit G at its lower end for drilling the central portion of the new hole. It also includes an expandable drill bit portion H for enlarging the bore hole produced by the pilot bit, by forming and operating upon a formation shoulder J, as hereinafter described.

The upper end of the expandable bit H consists of a driving mandrel 11, whose upper pin 12 is threadedly connected to a sub 13 forming the lower end of the drill pipe string B. This mandrel includes an upper kelly or drill stem member 14 slidably splined to the main body 15 of the bit. As disclosed in the drawings, the exterior 14a of the kelly is hexagonal in shape, and is telescopically received in a companion hexagonal socket 15a within the body. The mandrel 11 has a limited range of longitudinal movement within the body, its upward movement being limited by engagement of an external shoulder 16 on the kelly with a retainer ring 17 at the upper end of the body, suitably secured thereto, as by the use of welding material 18.

The body 15 has a plurality of expandable parts mounted on it, comprising cutter supporting members 19 pivotally mounted in body slots 20 on pivot or hinge pins 21 suitably secured to the body, as by the use of welding material 22. Each cutter supporting member consists of a depending leg 23, having a bearing supporting pin 24 inclined inwardly and downwardly, and on which a roller side cutter 25 is rotatably mounted. Anti-friction roller and ball bearing elements 26, 27 are preferably placed between each cutter 25 and bearing pin 24, the roller bearing 26 transmitting radial thrusts and the ball bearings 27 both radial and axial thrusts. The ball bearings 27 also retain each cutter on a pin, being inserted in place through a passage 28 in the bearing supports, which is then closed by a plug 29 welded to the pin 24. The plug or pin 29 depends from the passage 28, and is used to hold the cutters 25 in retracted position, as pointed out below.

Each cutter supporting member 19 also includes an upwardly extending arm 30, against which an elastic expander 31 bears. This expander, in the form of a compressed coil spring, is received within a retainer pocket 32 in the body 15, and exerts its force against the arm 30, tending to swing it inwardly and thus urge the cutter 25, on the other side of the fulcrum pin 21, in an outward direction. The extent of this outward movement is limited by engagement of stop shoulders 33, 33 on opposite sides of the cutter supporting member 19 with cooperable body stop shoulders 34, 34.

After the cutters 25 have been expanded outwardly by the expander springs 31 to the maximum extent, they can be locked in this position by a tubular member 35 of the mandrel 11, which is piloted in the kelly 14. This member is provided with a lock portion 47, movable from an upper position in transverse alignment with inner supporting member recesses 36, permitting retraction of the cutters, to a lower position opposite lugs 37 formed on and projecting inwardly from the supporting member legs 23, preventing retraction of the cutters.

The tubular member 35 is connected in swivel fashion to the kelly 14, to permit relative arcuate or rotary movement therebetween. However, the kelly and tubular member are coupled together

for longitudinal movement in both directions. This is accomplished by providing an anti-friction thrust bearing between a boss or shoulder 39 on the tubular member and the kelly 14. The shoulder 39 is received within a lower socket 14b in the kelly and has a toroidal raceway 70 on its exterior, around which a plurality of bearing balls 71 can ride. These balls are also received in an opposed toroidal raceway 72 in the kelly.

The balls 71 are insertable into the raceways through a hole or passage 73 extending through the external shoulder 16 on the kelly and communicating with its internal race 72. After the balls have thus been disposed in position, the hole is closed by a suitable pin or plug 74, which is prevented from moving outwardly of the kelly by the inner wall of the surrounding body 15.

The tubular member 35 has an upper portion 35a extending into the central bore 14d of the kelly, with the upper terminus 75 of the member 35a flaring upwardly and outwardly, to enable fluid pumped down the drill string B to flow smoothly into the central passage 35e through the tubular member 35. This fluid is prevented from flowing around the exterior of the tubular member 35 by suitable packing 77 disposed between the upper portion 35a of the tubular member and the kelly adjacent the upper end of the tubular member shoulder 39.

The arrangement between the tubular member 35 and kelly 14 is such that both downward and upward movement is transmitted between the kelly 14 and tubular member 35 from one raceway 70 or 72, through the ball bearing elements 71, to the other raceway 72 or 70. In this manner, the kelly 14 and tubular member 35 are caused to move jointly in both longitudinal directions, but they are free to partake freely of relative movement therebetween.

The mandrel 11 is normally held in its upper position with respect to the main body 15 of the bit and the supporting members 19 by a helical retractor spring 38 encircling the tubular member 35, with its upper end engaging the mandrel shoulder 39 and its lower end engaging a spring seat 40 at the lower end of the hexagonal body socket 15a. This spring seat 40 also serves as an upper bearing guide for the tubular mandrel member 35, whose lower end is slidably within a lower bearing guide 41 below the lugs 37, which bearing guide is integral with the main body 15 of the expandable bit and interconnects the depending webs 15c of the main body together. The two guides 40, 41 form a spaced two-point support for the mandrel member 35, and assist it in resisting inward movement of the cutter legs 23 to retracted position during the reaming or cutting operation.

The lower member 41 not only serves as a bearing guide for the tubular mandrel member 35, but it is also formed as a threaded box for receiving the upper threaded pin 80 of the lower non-expansive drill bit G. This drill bit may be of any desired form, being shown, for reasons of simplification, as a drag bit having cutter blades 81 capable of operating upon the bottom K of the bore hole. These cutter blades 81 have passages 82 extending from a central passage 83 in the pin portion 80 of the lower drill bit to the forward faces of each blade.

The tubular mandrel 35 extends downwardly below its guide 41, and preferably slidably into the central passage 83 in the lower drill bit G. Leakage around the exterior of the mandrel 35 may be prevented by providing a suitable side

seal 84 in a peripheral groove 85 on the mandrel 35 adapted to slidably and sealingly fit the walls of the central passage.

Circulating fluid can pass downwardly through the string of drill pipe B and through the tubular mandrel 11 into the central passage 83 of the lower drill bit G. From this point, the drilling fluid flows through the nozzles or passages 82 to the forward faces of the bit cutters 81, discharging from these cutters to cleanse them of cuttings and flush the latter from the drilling area to the top of the well bore. During its upward passage, the circulating fluid passes around the expandable cutters 25 and also maintains them clean of cuttings.

The cutters 25 may be retained initially in retracted position against the expandable forces of the springs 31 by means of a mechanically released trip device. This device includes a holding plate or member 86 disposed around the lower portion of the tubular member 35 immediately below an external flange 87 formed integrally with, or otherwise suitably secured to, the tubular member. The holding member has spaced holes 88 in its outer portion for receiving the lower ends 29 of the ball bearing plug or pins 29.

When the holding device 86 is disposed over the pins 29, the cutter supporting members 19 are prevented from expanding under the influence of the springs 31, thereby holding the cutters 25 in retracted position. It is to be noted that the pins 29 are inclined initially in a downward and slightly outward direction, so as to prevent the holding member from moving downwardly until purposely released, which downward movement would allow outward expansion of the cutters 25. Such release occurs as a result of downward movement of the tubular member 35, which will move its external flange 87 against the holding member 86 and shift it downwardly off the pins 29.

During lowering of the apparatus to the bottom of the hole, the holding device 86 retains the cutters 25 in retracted position. The effective diameter of the lower or pilot bit G is less than the inside diameter of the well casing C through which the drill bit apparatus is to pass, and this is also true of the retracted effective diameter of the expandable cutters 25. When the bottom K of the well bore has been reached, the pumps at the top of the hole are started and drilling fluid pumped down the drill string B. This drilling fluid passes through the tubular member 35 and through the pilot bit passage 83 and nozzles 82 to the bottom of the hole. Rotation of the drill string and the apparatus may then commence, to cause the pilot bit G to drill ahead in the well bore. At the commencement of such rotation, the drill string B, mandrel 11 and its tubular member 35 may be moved downwardly to a slight extent to cause the external mandrel flange 87 to engage the holding member 86 and to shift it downwardly sufficiently to remove it from the pins 29, freeing the cutters 25 and their supporting members 19 and allowing the springs 31 to expand. These springs will shift the arms 30 inwardly and the cutters 25 outwardly against the formation.

Rotation of the drill string B is continued, to rotate the expandable bit body 15 through the splined kelly and body connections 14a and 15a, until the side cutters 25 enlarge the diameter of the hole produced by the pilot bit to the maximum extent, as determined by eventual abutment of the supporting member stop shoulder 33 with the companion body stop shoulder 34. When

this full diameter has been achieved, a formation shoulder J has been produced in the well bore by the cutters 25 under the action of the expander springs 31. At this time, drilling weight may be imposed upon the drill string B, shifting its connecting mandrel 11 downwardly within the body 15 against the action of the retractor spring 38, until the lower end 48 of the kelly 14 engages the upper spring seat and guide 40. This downward movement also shifts the tubular member 35 downwardly; because of the interlocking ball thrust bearing 70, 71, 72, to position the mandrel or tubular member lock portions 47 opposite and in alignment with the lugs 37 on the inner portions of the cutter supporting members 19, providing a positive lock and preventing inward movement of the cutters 25 (Fig. 4).

It is to be noted that after the pilot bit G has reached the bottom K of the hole, the drill string B is lowered to only a slight extent, which is sufficient to engage the mandrel flange or shoulder 87 with the latch plate 86, and release it from the pins 29. The lock portion 47 is disclosed initially above the lugs 37 on the cutter supporting members 19, to allow the latch device 86 to be released without the lugs 37 offering any interference to lowering of the tubular mandrel 35. However, after such release, and following the production of the formation shoulder J, as exemplified in Fig. 4, the necessary drilling weight may be imposed on the drill string B, to produce proper penetration of the pilot bit cutting elements 81 into the formation, and disposition of the lock portion 47 in its locking position opposite and within the lugs 37.

During the downward telescoping of the tubular member 35 within the main bit body 15, its lower portion will also slide downwardly within the central passage 83 in the lower drill bit G. Fluid may be circulated through the drill bit, tubular mandrel and the pilot bit passages to insure proper flushing of the cuttings from the bottom of the hole and also from the area of the formation shoulder J to the top of the well bore.

Drilling is continued by rotating the drill bits H, G and imposing the proper drilling weight on the various cutters 81, 25, to cause their removal of the formation material at the bottom of the hole and enlarging of the pilot hole in a downward direction to the desired extent or length. When the drill bit is to be retracted and removed to the top of the well bore, the drill string B is elevated, which moves the side cutters 25 above the formation shoulder J and permits the retractor spring 38 to press relatively downward on the body 15 and move it, together with the cutter supporting members 19, downwardly with respect to the mandrel 11. This action repositions the mandrel lock portion 47 opposite the supporting member recesses 36, and above their lugs 37, because of the ball bearing coupling 11, permitting inward swinging of the cutters 25 and their supporting members 19 when the tool passes back into the casing C upon elevation of the drill string B. The cutters 25 and their supporting members 19 will ride the wall of the casing during elevation of the string B until the tool is removed from the top of the well bore. During this elevation, the latch plate 86 merely rests upon the upper end of the box portion 41 of the pilot bit body, without interfering with the operation of the equipment.

It is, accordingly, apparent that a rotary drill bit apparatus has been provided that is capable of producing a pilot hole, as well as enlarging the

hole to the desired diameter, which is greater than the inside diameter of the well casing C through which the apparatus is capable of passing. The expandible cutters 25 are held initially by positive means in retracted position, and are removed mechanically by positive means when the bottom of the well bore is reached. Release of the cutter latch 86 is effected by the tubular member 35, which serves to lock the cutters 25 outwardly in their fully expanded position. This locking member also insures the delivery of an adequate volume of drilling fluid to the pilot bit G, and also insures the removal of the cuttings from the bottom K of the well bore, as well as from the region of the formation shoulder J.

The inventor claims:

1. A rotary well drilling bit: including a main body; cutter means mounted on said body for lateral movement with respect to said body; a mandrel slidably splined to said body and adapted for connection to a tubular drill string; means engaging said cutter means for expanding said cutter means laterally outward independently of movement of said mandrel along said body; releasable latch means connected to said cutter means for releasably holding said cutter means in an inward position against the action of said expanding means; and means on said mandrel movable therewith, and engageable with said latch means to release said latch means from holding said cutter means in an inward position upon movement of said mandrel relative to said body.

2. A rotary well drilling bit: including a main body; cutter means mounted on said body for lateral movement with respect to said body; a mandrel slidably splined to said body and adapted for connection to a tubular drill string; means engaging said cutter means for expanding said cutter means laterally outward independently of movement of said mandrel along said body; releasable latch means connected to said cutter means for releasably holding said cutter means in an inward position against the action of said expanding means; means on said mandrel movable with said mandrel in one longitudinal direction along said body, after expansion of said cutter means, into engagement with said cutter means for preventing inward movement of said cutter means; and means on said mandrel movable therewith, and engageable with said latch means to release said latch means from holding said cutter means in an inward position upon movement of said mandrel in said one longitudinal direction.

3. A rotary well drilling bit: including a main body; cutter means mounted on said body for lateral movement with respect to said body; a mandrel slidably splined to said body and adapted for connection to a tubular drill string; means engaging said cutter means for expanding said cutter means laterally outward independently of movement of said mandrel along said body; latch means disposed around said mandrel and releasably connected to said cutter means for releasably holding said cutter means in an inward position against the action of said expanding means; and means on said mandrel engageable with said latch means for releasing said latch means from said cutter means upon movement of said mandrel relative to said body.

4. A rotary well drilling bit: including a main body; cutter means mounted on said body for lateral movement with respect to said body; a mandrel slidably splined to said body and

adapted for connection to a tubular drill string; means engaging said cutter means for expanding said cutter means laterally outward independently of movement of said mandrel along said body; latch means disposed around said mandrel and releasably connected to said cutter means for releasably holding said cutter means in an inward position against the action of said expanding means; means on said mandrel movable with said mandrel in one longitudinal direction along said body, after expansion of said cutter means, into engagement with said cutter means for preventing inward movement of said cutter means; and means on said mandrel engageable with said latch means for releasing said latch means from said cutter means upon movement of said mandrel in said one longitudinal direction.

5. A rotary well drilling bit adapted to be connected to a tubular drill string: including a main body; cutter means carried by said body and movable laterally of said body; means engaging said cutter means for expanding said cutter means laterally outward; releasable latch means connected to said cutter means for releasably holding said cutter means in an inward position against the action of said expanding means; and means connectable to the drill string and slidably within said body into engagement with said latch means, in response to longitudinal movement of the drill string, for releasing said latch means from holding said cutter means in an inward position.

6. A rotary well drilling bit: including a main body; cutter means mounted on said body for lateral movement with respect to said body; means engageable with said cutter means for expanding said cutter means laterally outward and for preventing inward movement of said cutter means from such outward position, said engageable means comprising a mandrel slidably splined to said body and adapted for connection to a tubular drill string; releasable latch means connected to said cutter means for releasably holding said cutter means in an inward position; and means on said mandrel movable therewith, and engageable with said latch means to release said latch means from holding said cutter means in an inward position upon longitudinal movement of said mandrel relative to said body.

7. A rotary well drilling bit: including a main body; cutter means mounted on said body for lateral movement with respect to said body; means engageable with said cutter means for expanding said cutter means laterally outward and for preventing inward movement of said cutter means from such outward position, said engageable means comprising a mandrel slidably splined to said body and adapted for connection to a tubular drill string; latch means disposed around said mandrel and releasably connected to said cutter means for releasably holding said cutter means in an inward position; said mandrel being engageable with said latch means for releasing said latch means from said cutter means upon longitudinal movement of said mandrel relative to said body.

8. A rotary well drilling bit: including a main body; cutter means mounted on said body for lateral movement with respect to said body; means engageable with said cutter means for expanding said cutter means laterally outward and for preventing inward movement of said cutter means from such outward position, said engageable means comprising a mandrel slidably

splined to said body and adapted for connection to a tubular drill string for longitudinal movement thereby in one direction to a position holding said cutter means outwardly; releasable latch means connected to said cutter means for releasably holding said cutter means in an inward position; and means on said mandrel movable therewith, and engageable with said latch means to release said latch means from holding said cutter means in an inward position upon movement of said mandrel in said one longitudinal direction.

9. A rotary well drilling bit: including a main body; cutter means mounted on said body for lateral movement with respect to said body; a drill bit secured to the lower end of said main body, said drill bit having a fluid circulating passage; means engageable with said cutter means for expanding said cutter means laterally outward and for preventing inward movement of said cutter means from such outward position, said engageable means comprising a tubular mandrel extending into said passage and slidably splined to said body, means on said mandrel for connecting said mandrel to a tubular drill string.

10. A rotary well drilling bit: including a main body; cutter means mounted on said body for lateral movement with respect to said body; a drill bit secured to the lower end of said main body, said drill bit having a fluid circulating passage; means engageable with said cutter means for expanding said cutter means laterally outward and for preventing inward movement of said cutter means from such outward position, said engageable means comprising a tubular mandrel extending into said passage and slidably splined to said body, means on said mandrel for connecting said mandrel to a tubular drill string; and means providing a slidable seal between said mandrel and passage.

11. A rotary well drilling bit: including a main body; cutter means mounted on said body for lateral movement with respect to said body; a drill bit secured to the lower end of said main body, said drill bit having a fluid circulating passage; means engageable with said cutter means for expanding said cutter means laterally outward and for preventing inward movement of said cutter means from such outward position, said engageable means comprising a tubular mandrel extending into said passage and slidably splined to said body, means on said mandrel for connecting said mandrel to a tubular string; releasable latch means disposed around said mandrel and connected to said cutter means for releasably holding said cutter means in an inward position; and an external flange on said mandrel engageable with said latch means for releasing said latch means from said cutter means.

12. A rotary well drilling bit: including a main body; cutter means mounted on said body for lateral movement with respect to said body; a drill bit secured to the lower end of said main body, said drill bit having a fluid circulating passage; a tubular mandrel extending into said passage and slidably splined to said body, said mandrel being adapted for connection to a tubular drill string; means engaging said cutter means for expanding said cutter means laterally outward independently of movement of said mandrel along said body; latch means disposed around said mandrel and releasably connected to said cutter means for holding said cutter means in an inward position against the action of said expanding means; means on said mandrel engageable

with said latch means for releasing said latch means from said cutter means upon movement of said mandrel in one longitudinal direction; and means on said mandrel movable with said mandrel in said one longitudinal direction into engagement with said cutter means for preventing inward movement of said cutter means.

13. A rotary well drilling bit: including a main body; cutter means mounted on said body for lateral movement with respect to said body; a drill bit secured to the lower end of said main body, said drill bit having a fluid circulating passage; a tubular mandrel extending into said passage and slidably splined to said body, said mandrel being adapted for connection to a tubular drill string; means engaging said cutter means for expanding said cutter means laterally outward independently of movement of said mandrel along said body; releasable latch means disposed around said mandrel and connected to said cutter means for releasably holding said cutter means in an inward position against the action of said expanding means; an external flange on said mandrel engageable with said latch means for releasing said latch means from said cutter means upon downward movement of said mandrel; and means on said mandrel movable downwardly with said mandrel into engagement with said cutter means for preventing inward movement of said cutter means.

14. A rotary well drilling bit: including a main body; cutter means mounted on said body for lateral movement with respect to said body; a mandrel slidably splined to said body and adapted for connection to a tubular drill string; means engaging said cutter means for expanding said cutter means laterally outward independently of movement of said mandrel along said body; latch means disposed around said mandrel and releasably connected to said cutter means for holding said cutter means in an inward position against the action of said expanding means; first means on said mandrel movable with said mandrel in one longitudinal direction along said body, after expansion of said cutter means, into engagement with said cutter means for preventing inward movement of said cutter means; and second means on said mandrel engageable with said latch means for releasing said latch means from said cutter means upon movement of said mandrel in said one longitudinal direction; said first means and second means being spaced on said mandrel with respect to each other so that said second means engages and releases said latch means upon movement of said mandrel in said one longitudinal direction prior to location of said first means in position to prevent inward movement of said cutter means.

15. A rotary well drilling bit: including a main body having a lower threaded member; cutter means mounted on said body for lateral movement with respect to said body; a drill bit threadedly connected to said lower member, said drill bit having a fluid circulating passage; means engageable with said cutter means for expanding said cutter means laterally outward and for preventing inward movement of said cutter means from such outward position, said engageable means comprising a tubular mandrel extending into said lower threaded member and slidably splined to said body, means on said mandrel for connecting said mandrel to a tubular drill string.

16. A rotary well drilling bit: including a main body; cutter means mounted on said body for lateral movement with respect to said body; a

11

mandrel slidably splined to said body and adapted for connection to a tubular drill string; means engaging said cutter means for expanding said cutter means laterally outward; latch means connected to said cutter means for releasably holding said cutter means in an inward position; and an operative connection between said latch means and said mandrel, whereby said latch means is released when said mandrel is moved relative to said body.

17. A rotary well drilling bit: including a main body; cutter means carried by said body for lateral movement with respect to said body; means engaging said cutter means for expanding said cutter means laterally outward; latch means connected to said cutter means for releasably holding said cutter means in an inward position; instrumentalities movable with respect to said body and operatively connected to said latch means to

12

5 release said latch means from said cutter means upon longitudinal movement of said instrumentalities relative to said body; and means on said instrumentalities for connecting said instrumentalities to a tubular drill string to enable said instrumentalities to be moved longitudinally of said body by the tubular drill string to effect such release of said latch means.
